valve or distributing valve and a piston which will be reciprocated with respect to the piston chamber, the piston being provided with a valve structure for controlling the flow of pressure fluid to and from the piston chamber.

UNITED STATES PATENT OFFICE

VALVE FOR ROCK DRILLS

Paul H. Nast, West Springfield, Mass., assignor to Worthington Pump and Machinery Corporation, Harrison, N. J., a corporation of Delaware

Application February 25, 1948, Serial No. 10,612

2 Claims. (Cl. 121—28)

1

This invention relates to rock drills and more particularly to a distributing valve for controlling distribution of operating pressure fluid to the actuated mechanism of a percussive rock drill.

An object of the present invention is to provide a distributing valve structure which will insure rapid and positive action of the valve; and assure a heavy and forceful blow of the percussive element against the working tool and one which is of simplified design and low cost of manufacture.

The present invention comprehends a distributing valve structure wherein the valve is tripped by fluid pressure acting on the valve area, such pressure fluid being ported from the rock drill cylinder or piston chamber and controlled by movement of the piston and a valve distributing structure which embodies valve laps which cooperate with the valve to close one port before the other is opened, thus eliminating any opposed action of pressure air on opposite sides of the piston even for an instant and, consequently, reducing air consumption of the tool and increasing its efficiency.

More specifically, the invention embodies the combination of a valve stem on which a valve of uniform diameter reciprocates, said stem being provided with pressure supply passages which open through annular air grooves to supply air to the cylinder and which air grooves are arranged or positioned so that the valve laps are formed when the valve box cover and valve box are assembled, thus eliminating intricate and costly machining of either the valve, the valve box or the valve box cover and providing the valve structure which may be ground to exact dimensions, as well as providing perfect alignment of the parts so as to eliminate binding or crowding of the valve during operation.

With these and other objects in view, as may appear from the accompanying specification, the invention consists of various features of construction and combination of parts, which will be first described in connection with the accompanying drawings, showing a valve for rock drills of a preferred form embodying the invention, and the features forming the invention will be specifically pointed out in the claims.

In the drawings:

Figure 1 is a fragmentary longitudinal section through a rock drill showing the improved valve structure.

Figure 2 is a cross section taken on the line 2—2 of Figure 1.

Figure 3 is a fragmentary longitudinal section through the rock drill taken on a different plane than that shown in Figure 1.

Figure 4 is a perspective view of the valve supporting pressure air delivering valve stem.

Figure 5 is a cross section taken on line 5—5 of Figure 4.

Figure 6 is a perspective view of the valve.

Referring more particularly to the drawings, the improved valve structure for rock drills shown in Figure 1 is assembled in a pressure air or pressure fluid actuated rock drill comprising a housing 1 having a piston chamber 2 formed therein in which the piston 3 reciprocates under action of pressure air controlled by the valve structure which forms the present invention. As is usual in pressure fluid actuated rock drills, the piston 3 delivers blows against the drill steel (not shown) or other tool operated by the rock drill proper.

The cylinder 2 has an exhaust passage 4 opening out through an exhaust valve structure 5 to the atmosphere. The usual approved type of ratchet mechanism 6 is mounted in the rear end of the housing 1 and serves to rotate the tool (not shown) in the usual manner. The valve structure or assembly 7 is positioned between the ratchet mechanism 6 and the rearward end of the piston chamber 2 and pressure fluid is delivered to the valve structure 7 from a suitable source of supply of pressure air (not shown) under control of an approved type of throttle valve 8 through the passage 9 in the head 10 of the drill structure, and through the space 11 surrounding the ratchet mechanism.

The distributing valve structure comprises a valve box 12, a valve box cover 13, a valve stem 14 and the valve 15. The valve stem 14 is cylindrical in construction and has an annular flange 16 formed on its rearward end, which annular flange is provided with an annular passage or groove 17 having communication with the space 11 so as to receive pressure fluid thereinto from

the passage 9 and deliver it to a plurality of longitudinally extending annularly or circumferentially spaced passages 19 formed in the valve stem. The valve stem 14 is provided with a pair of spaced annular air outlet grooves 20 and 21.

The spaced annular groove 20 has communication with all of the longitudinally extending air passages 19 and with an annular passage 22 formed in the valve box cover. The housing 1 of the rock drill is provided with ports and passages 23 which establish communication between the annular passage 22 and the piston chamber 2 at or near the forward end of the piston chamber, as shown at 24, to supply pressure fluid to the forward end of the piston chamber in advance of the piston

3 for returning the piston to its rearward position in the piston chamber 2.

The valve box 12 is provided with a plurality of passages 25 which communicate with the annular passage 21 and with the rear end of the piston chamber 2 for delivering pressure fluid behind the piston 3 for moving it on its forward blow imparting stroke.

The passage of the pressure fluid through the annular passage 22 and the passages 25 is controlled by the distributing valve 15 which is mounted for limited reciprocatory movement upon the valve stem 14 and in a suitable space within the valve box 12 and valve box cover 13.

The valve 15 has an annular flange 26 formed thereon which extends into an annular recess 27 in the valve box 12. The annular recess 27 is wider or deeper than the width of the flange 26 so as to provide a space at either side of the flange 26, depending upon the position of the valve 15 and of the piston 3.

The housing 1 is provided with ports and passages indicated at 27' which open into the piston chamber 2 forwardly of the exhaust passage 4 and open into the annular recess 27 at the forward end of this annular space so that as the piston returns on its rearward movement and uncovers the inlet of the passage 27' pressure air will be admitted from the piston chamber 2 into the annular recess 27 at the forward side of the flange 26 and move the valve 15 rearwardly to cut off communication between the annular passage 22 with the piston chamber 2 through the passage 23 and open the annular inlet groove 21 to the passages 25 to admit pressure fluid to the piston chamber behind the piston to move it on its forward blow delivering stroke.

The housing 1 is also provided with a passage 28 which is ported to the piston chamber 2 rearwardly of the exhaust passage 4 and is also ported to the annular space 27 at the rear side of the flange 26 so that as the piston moves forwardly and uncovers the port of communication between the passage 28 and the piston chamber 2 air will be admitted to the passage 28 and against the rearward side or face of the flange 26 for forcing the valve 15 forwardly to cut off communication between the annular pressure fluid inlet passage 21 and the passages 25 to cut off flow of pressure fluid into the piston chamber 2 rearwardly of the piston.

In operation therefore, pressure fluid from a suitable source (not shown) is delivered by manually opening the throttle valve 8 to allow the pressure to pass through the passage 9 through the space 11 surrounding the ratchet mechanism 6 into the annular passage or groove 17 communicating with the said space 11.

The pressure fluid expands into the longitudinal passages 19 passing into the annular air outlet grooves 20 and 21, where depending on the position of the valve 15 will pass to either one or the other of the annular recesses 22 or 34, and accordingly the drill structure or housing 1 may be tilted substantially vertically upwardly or downwardly to force the valve by action of gravity so it will abut either the valve box cover 13 or the portion 33. The piston member 3 will also fall rearwardly or forwardly accordingly.

In normal operation the valve 15 will abut the portion 33 and the piston will be forward in the cylinder 2, thus air will expand into the annular space 22, the passage 23 communicating therewith and discharge through the outlet 24 to move the piston 3 rearwardly substantially as is indicated in Figure 1 of the drawings.

The portion of the cylinder rearwardly of the

piston member 3 is under atmospheric pressure and accordingly offers little resistance to the piston members rearward movement so that the inlet of the passage 27' is uncovered and receives pressure fluid therein which expands to the forward area of the annular recess 27 to move the valve 15 in a rearward direction which cuts off the pressure fluid entering the annular space 22 and allows the pressure fluid to enter the annular space 34 to pass through the passage 25 into the cylinder 2 rearwardly of the piston member 3. This will stop the rearward motion and start the piston on its forward stroke.

As the piston moves forwardly it uncovers the inlet to the passage 28 and pressure fluid therein will flow through passage 28 into the rearward area of the annular recess 27 causing the valve 15 to move forwardly which cuts off the pressure fluid entering the annular space 34 and allows the pressure fluid to enter the annular passage 22 once again wherein the pressure fluid will pass down passage 23 to the outlet 24 to move the piston on its rearward stroke.

It can readily be seen that the same action will occur if the valve abuts the valve box 13 initially except that the action will commence by moving the piston member 3 forwardly first.

As clearly shown in Figure 1 of the drawings, the valve box 12, valve box cover 13 and the annular flange 16 on the valve stem 14 are all of uniform external diameter and fit snugly within the valve structure receiving bore formed in the housing 1. The valve box 12 has its portion 33 driven on the valve stem 14 and serves the dual function of holding the valve stem 14, valve box cover 13 and valve box 12 all in tightly fitting assembled position as well as an abutment for the forward end of the valve 15.

The annular pressure air inlet grooves 20 and 21 and the annular inlet passage 22 and the annular portion 34 of the passages 25 are all constructed and arranged so that when the valve box 12, valve box cover 13 and valve stem 14 are in assembled positions, laps, indicated at 35 and 36 will be provided at the ends of the valve 15 so that during operation of the rock drill communication between one of the pressure air annular inlet grooves 20 or 21 with its corresponding annular passage 22 or 34 will be cut off completely before communication is established between the other set and thereby opposed action of pressure air against the piston 3 even for an instant will be eliminated.

Also by reference to Figure 1 of the drawings, it will be noted that the valve 15 is of uniform external and internal diameter throughout its length except that its external diameter may be said to be increased by the flange 26 and also that the valve 15 is free of any undercuts or ports or passages therein and thus expensive and delicate machining operations are eliminated in the construction of the valve, as well as in the construction of the valve stem, valve box and valve box cover and these parts may be accurately ground. Furthermore, the construction of the valve of the distributing valve structure or rather of its component parts is such that perfect alignment of all of the parts may be had and extremely close fits provided. Any misalignment of the valve stem would tend to bind or crowd the valve, preventing it from having free action. The valve stem is supported at the rear by the flange 16 and at the front by the portion 33 of the valve box 12. The simplified construction of the component parts of the distributing

valve structure which permits grinding of these component parts and eliminates costly and intricate machining of laps, undercuts or the like, such as is usually found in valves of this type, as well as elimination of dowels to hold the parts together provides a simplified efficient design of relatively low manufacturing cost.

It will be understood that the invention is not to be limited to the specific construction or arrangement of parts shown, but that they may be 10 widely modified within the invention defined by the claims.

What is claimed is:

1. In a percussive tool, a housing having a piston chamber therein, a reciprocatable piston in 15 said chamber, an exhaust port for said chamber, and a distributing valve structure including a valve box with a valve stem therein, said valve box having a first air inlet passage formed there-in communicating with the rear end of the piston 20 chamber, a second air inlet passage formed in said valve box and said housing communicating with the forward end of said piston chamber, said valve stem having an annular groove in the upper end for communication with a 25 source of pressure air supply, a plurality of longitudinally extending circumferentially spaced passages in said valve stem communicating with said annular groove for receiving pressure air therein, an upper and a lower annular air outlet 30 passage formed on the outer circumference of said valve stem to provide lateral communication between said circumferentially spaced passages and said air inlet passages, a valve slid-ably mounted about said valve stem having a 35

constant inner diameter substantially equal to the outer circumference of said valve stem, a flange on the outer circumference of said valve, a front and rear supply passage disposed on opposite sides of said housing providing communication between said piston chamber and opposed surfaces of said flange to allow air under pressure to move said valve whereby the flow of pressure air from said circumferentially spaced passages through said annular air outlet passages to reciprocate said piston will be controlled.

2. In a percussive tool as claimed in claim 1 wherein said valve stem and valve are supported in said valve box by an annular member having a driven fit over the end of said valve stem about its outer circumference adjacent and inwardly of said first air inlet passages in said valve box.
